Conklin Pen Company, Toledo, Ohio, a corpo-
ration of Ohio

Application May 11, 1936, Serial No. 62,581

Term of patent 7 years

To all whom it may concern:

Be it known that I, Thomas Emerson, a citizen of the United States and resident of Toledo, in the county of Lucas and State of Ohio, have invented a new, original, and ornamental Design for a Combined Article Case and Display Holder, of which the following is a specification, reference being had to the accompanying drawing forming a part thereof.

In the drawing, Fig. 1 is a top perspective view of a combined article case and display holder in closed form showing my new design; Fig. 2 is a perspective view thereof with the top member of the case removed and with the bottom member

in open article displaying position, and Fig. 3 is an end view of the member shown in Fig. 2.

The dominant feature of my design consists in the appearance of the bottom member thereof in its open position as shown in Fig. 2, the outwardly facing panels being of a reflective nature.

I claim:

The ornamental design for a combined article case and display holder, substantially as shown and described.

In testimony whereof I have hereunto signed my name to this specification.

THOMAS EMERSON.
